UNITED STATES PATENT OFFICE

150,468

DESIGN FOR A WHEELED TOY HORSE
AND CHARIOT

Harry Sebel, London, England

Application May 16, 1946, Serial No. 129,758

Term of patent 14 years

(Cl. D34—15)

To all whom it may concern:

Be it known that I, Harry Sebel, a subject of the King of Great Britain, residing at London, England, have invented a new, original, and ornamental Design for a Wheeled Toy Horse and Chariot, of which the following is a specification, reference being had to the accompanying drawing, forming part thereof.

Fig. 1 is a front perspective view of a wheeled toy horse and chariot, showing my new design;

Fig. 2 is a rear perspective view of the toy shown in Fig. 1; and

Figs. 3 and 4 are, respectively, sectional views taken along the lines 3—3 and 4—4 of Fig. 1.

I claim:

The ornamental design for a wheeled toy horse and chariot, as shown.

HARRY SEBEL,
